CARRIER FOR BOMBS OR THE LIKE FOR AIRCRAFT

Edward J. Horkey, Rolling Hills, and William C. Armstrong, Orange, Calif., assignors, by mesne assignments, to Northrop Corporation, Hawthorne, Calif., a corporation of California

Application March 18, 1958, Serial No. 50,084

Term of patent 14 years

(Cl. D71—1)

Figure 1 is a top perspective view of a carrier for bombs or the like for aircraft embodying our new design.

Figure 2 is a left-hand elevational view thereof, the opposite side being the same in appearance.

Figures 3 and 4 are top and bottom plan views, respectively, thereof; and

Figure 5 is a front elevational view of the carrier for bombs or the like for aircraft.

The broken line portion of bombs shown in Figure 2 is for illustrative purposes only.

We claim:
The ornamental design for a carrier for bombs or the like for aircraft, as shown and described.
